UNITED STATES PATENT OFFICE.

CHARLES H. PRIESTLEY, OF ELIZABETH, NEW JERSEY.

ELECTRIC FURNACE.

1,380,248.

Specification of Letters Patent.

Patented May 31, 1921.

Application filed April 24, 1919. Serial No. 292,329.

To all whom it may concern:

Be it known that I, CHARLES H. PRIESTLEY, a citizen of the United States, and a resident of Elizabeth, county of Union, and

5 State of New Jersey, have invented a new and Improved Electric Furnace, of which the following is a full, clear, and exact description.

This invention relates to electric furnaces.

10 More particularly the invention relates to an electric furnace in which there may be generated extremely high temperatures or super-temperatures, for the purpose of melting materials.

15 An object of the invention is to provide an electrical furnace in which may be produced extremely high temperatures, and which furnace will be able to withstand increasing gas or air pressure incident to the generating

20 of the temperature.

It is a further object of the invention to provide an electrical furnace in which materials may be changed from solid state to liquid state, and at the same time employ

25 pressure producing elements for preventing vaporization of the materials to be melted. A feature of the invention resides in the accessibility of all furnace parts, making it possible to quickly assemble and disassemble the electrical furnace.

With the above and other objects in view the invention has relation to a certain combination and arrangement of parts, an example of which is described in the following

35 specification, pointed out in the appended claims, and illustrated in the accompanying drawings, wherein:

Figure 1 shows the electrical furnace is longitudinal cross sectional view.

40 Fig. 2 shows a cross section taken upon the line 2—2 of Fig. 1.

Fig. 3 shows a cross sectional view taken upon the line 3—3 of Fig. 1.

Figs. 4 and 5 show views of a closure cap

45 employed on the furnace.

Referring more in particular to the drawings, wherein the same parts of the furnace throughout the several views are designated by the same reference characters, the nu-

50 meral 1 points out a retaining frame or band member comprising the two parallel sides joined integrally at the end thereof as designated by 2, and provided with a screw-threaded boss 3 at the forward end of said band. The stud of the frame is bored and tapped for a heavy clamp screw 4.

A furnace cylinder 6 with accessory parts is confined within the retaining frame. The furnace cylinder is fitted on the interior bore with a heavy insulating tube 7 of 60 the same length as the furnace cylinder, and the insulating tube may be made of zirconium oxid.

A circuit conductor plug comprising sections of current conducting electrodes 9 and 10, is inserted in each end of the insulating tube. As later seen the temperature producing current will be led through these electrodes. An insulator cap 12 is placed over each end of the furnace cylinder and placed 70 in contiguous relation with the insulating tube.

A closure cap comprising a solid head 13 grooved out as indicated by 14, is placed over each end of the furnace cylinder and in contact with the insulator caps such that said caps will be backed up and supported by the closure heads. The cap is grooved across the inner face thereof as illustrated which adapts it to receive a circuit electrode 15. 80 The circuit electrodes 15 are pushed in through the opening left between the electrode plugs and insulator caps. The circuit electrode will be shaped to accurately fit the form or groove of the insulator cap. 85 The electrode will be fitted with suitable conducting wires 16 connected with a head 17 which is clamped to the circuit electrode, or which may be an integral part thereof.

The inner space bounded by the heavy insulated walls of the insulating tube forms a furnace chamber in which the high temperature and high pressure will be generated, and into this chamber will be placed the material to be melted or subjected to the 95 electro-chemical process which comprises another subject of patentable application, disclosed in my application for patent filed April 29th 1919, Serial No. 292,533. Any material to be melted and crystallized will be 100 introduced into the furnace chamber and supported between the electrode plugs. In this instance there is shown what may be called a carbon rod A which it is proposed to melt and electro-chemically produce crystals such as diamonds or other materials. 105 This carbon rod A will preferably be supported in carbon plugs B, and the electrode plugs 9 and 10 pushed inwardly against the carbon plugs to form adequate contacts.

110 The furnace assembly with its contacts will be placed in the retaining frame and

the clamp screw compressively engaged with the closure head. This will bring the closure head into close fitting engagement with the furnace parts and provide liquid 5 and gas tight fits between all parts.

- The retaining frame, furnace cylinder and closure head will be built of material most suitable for this purpose. Steel or other strong materials will be selected for the construction of this furnace, and all parts be so constructed as to be able to withstand the super-infinite pressure which will be developed within the furnace chamber when the electro-chemical process is undertaken.
- 10 The circuit wires 16 will be placed in an electrical circuit capable of furnishing extremely large quantities of electrical energy. The current will act upon the carbon rod A or other material, and through the resistance of the rod to be melted, will raise said rod to extremely high temperature.
- 15
- 20

It may be desirable to introduce certain other materials within the furnace chamber. One purpose will be to insert a material 25 for producing an expanding gas pressure so as to prevent volatilization of the carbon rod when said rod is heated to the super-temperatures employed within the furnace. It may also be desirable to employ a solid 30 body material to be packed within and around the rod in order that said rod may be supported and retained in a liquid state and prevented from working a molecular disassociation of structure.

- 35 This form of electric furnace can be used for producing artificial crystals from any material determined suitable by experimentation. Carbon rod or granulated carbon material is one form of substance which may 40 be crystallized within the furnace for producing hard crystals of the gem variety such as diamonds, and the like.

In my application for Letters-Patent filed April 29, A. D. 1919, and Serial Number 45 293,533, I have disclosed a patentable proc-

ess for electro-chemical production of gem materials and crystallized substances. Within that disclosure will be found the elements and directions for carrying out the electro-chemical production of the aforesaid substances. The electro-chemical furnace herein disclosed is primarily designed for carrying out the process of producing the crystallized substances as above mentioned.

Having thus described my invention, what 55 I claim as new, and desire to secure by Letters Patent is:

1. An electric furnace, comprising in combination; a retaining frame, a clamping cap screw screw-threaded within the retaining frame, a furnace cylinder, an insulating tube inserted within the furnace cylinder to line said cylinder, a grooved closure head, insulator caps placed upon each end of the furnace cylinder and against the insulator cap 60 with the cap confined within the groove of the closure head, and circuit electrodes inserted within the groove of the insulator cap and passed across the bore of the furnace cylinder.

2. An electric furnace, comprising in combination; a furnace cylinder, an insulating tube contained within the cylinder, an electrode plug inserted within each end of the insulator tube, a material to be crystallized 75 inserted within the tube between the electrode plugs, grooved closure heads applied to the furnace cylinder ends, and a circuit electrode inserted between the electrode plug and closure head for the purpose of conducting current to the material to be crystallized.

3. An electric furnace comprising: a retaining frame, a furnace cylinder, closure heads applied to the furnace cylinder and provided with slotted openings formed 85 therethrough, and circuit electrodes carried within the slotted openings to transmit current to the interior of the furnace.

CHARLES H. PRIESTLEY.
